UNITED STATES PATENT OFFICE.

ARTHUR L. GARFORD, OF ELYRIA, OHIO.

DESIGN FOR A BICYCLE-SADDLE SEAT.

SPECIFICATION forming part of Design No. 28,382, dated March 15, 1898.

Application filed September 15, 1897. Serial No. 651,799. Term of patent 14 years.

To all whom it may concern:

Be it known that I, ARTHUR L. GARFORD, citizen of the United States, residing at Elyria, in the county of Lorain and State of Ohio, have invented and produced a new, useful, and original Design for a Bicycle-Saddle seat, of which the following is a full, clear, and exact description, reference being had to the accompanying drawings, forming a part hereof.

In the drawings, Figure 1 is a plan view of the saddle. Fig. 2 is a side elevation thereof, and Fig. 3 is a sectional view on line 3 3 of Fig. 2.

The leading features of my design consist of a substantially pear-shaped seat of considerable thickness, having its broad rear end curved upward and having a lenticular hole formed longitudinally in its middle part and having its top surface at each side of the front end of said hole forming rounded parts the tops of which are above the level of the surface of the saddle immediately in front of them, the top surface of the seat curving

downward toward and uniting with the bottom surface at the marginal edges and the edges of said hole.

Referring to the parts by letters, A represents the horn or pommel part of the seat, and B the upwardly-curved broad rear part of the seat, and C the intermediate part, these three parts together giving the pear-shaped form to the seat.

D represents the lenticular hole, and E the two rounded points on opposite sides of the front end of the hole, which points are above the surface of the horn part B just in front of them.

I claim—

The design for a bicycle-saddle seat, substantially as herein shown and described.

In testimony whereof I affix my signature in presence of two witnesses.

ARTHUR L. GARFORD.
